PRODUCTION OF MOTOR FUEL

Jean P. Jones, Bartlesville, Okla., assignor to
 Phillips Petroleum Company, a corporation of
 Delaware

Application October 21, 1940, Serial No. 362,145

2 Claims. (Cl. 260—683.4)

This invention relates to the production of higher molecular weight hydrocarbons from hydrocarbons of lower molecular weight. More particularly, this invention relates to the production of a motor fuel or motor fuel blending stock containing aliphatic hydrocarbons which are highly branched, and have a molecular weight of 112 or more, from low boiling hydrocarbon materials comprising predominantly normal paraffins. This application is a continuation-in-part of my co-pending application Serial No. 300,462 filed October 20, 1939.

The production of large quantities of motor fuels in the motor fuel boiling range and with high antidentalinating characteristics is of increasing importance. The antidentalinating qualities or characteristics of a motor fuel are ordinarily expressed by the well known "octane number," a fuel having good antidentalinating characteristics having a high octane number. More gasoline is consumed by automobile motors than by motors used for any other purpose, and the average octane number of regular grades of automotive gasoline is now about 73, whereas during 1932 it was only about 62 and during 1935 it was about 68. Although considerably less fuel is used in airplane motors, the recent increase in the amounts used and in the average octane numbers is quite marked, as evidenced by the following table.

Military aviation gasoline (United States)

Year	Barrels	Average octane number
1932	461,869	82
1933	519,894	87
1934	563,026	90
1935	608,081	91
1936	756,152	93
1937	870,088	95
1938	1,069,932	1 ¹ 98
1939	1,514,000	1 ¹ 00+

¹ Estimated.

Several things of striking interest are brought out by a consideration of this table. Aviation motors require a fuel with a much higher octane number than do automotive motors; the amount of high octane number gasoline required by the U. S. Army alone has almost trebled in the last six years; and the average octane number of aviation gasoline has increased quite markedly. There is another fact which is not apparent from this table and which is likewise of considerable importance. In 1933, although the average octane

number of aviation gasoline was only 87, refiners were allowed to include in the gasoline up to 6 cc. of tetraethyl lead per gallon of gasoline, in order to produce a fuel with this octane number. However, in 1939 considerable quantities of aviation gasoline with an octane number of 100 are being used, and in producing this gasoline refiners are generally allowed to use only 3 cc. of tetraethyl lead per gallon of gasoline. Thus, not only is the amount of aviation gasoline required increasing rapidly, and the quality of this gasoline as represented by its octane number increasing rapidly, but the requirements and restrictions with respect to the actual hydrocarbons used for aviation gasoline are becoming restricted even more rapidly. In addition to octane number requirements, aviation gasoline must have a high stability as to gum and color formation. Requirements along this line make the production of paraffin hydrocarbons having high octane numbers of major importance because these hydrocarbons also are quite stable as to gum and color formation.

One of the most desirable of these hydrocarbons is the well known iso-octane (2,2,4-trimethylpentane). One of the principal sources of supply of this hydrocarbon is in the isobutylene content of the so-called "cracked gases" produced by oil cracking. When this isobutylene is polymerized to form di-isobutylene, and this product is saturated with hydrogen by nondestructive hydrogenation, 2,2,4-trimethylpentane results. This hydrocarbon can also be formed from isobutane present in natural gas by first dehydrogenating the isobutane to isobutylene. In either case the amount of valuable hydrocarbons which can be produced in this manner is limited to the actual amount of isobutylene, or isobutane, available.

However, it has been found possible to treat a refinery butane-butene fraction, which contains both isobutylene and normal butylenes, in such a manner that isobutylene will react with normal butylenes to produce co-polymers. These co-polymers can be hydrogenated to produce octanes somewhat similar to the well known 2,2,4-trimethylpentane, but of slightly inferior octane numbers. However, the octane numbers of the products from this operation are well above 90 and those products show a good response to the addition of agents such as tetraethyl lead. Such a method therefore increases considerably the amount of aviation gasoline with an octane number of about 100 which can be produced from the isobutylene present in a refinery butane-butene fraction. It has also been found possible to produce such highly branched paraffin hydrocarbons

by direct union of isoparaffins and olefins in alkylation processes.

I have now invented a process whereby large quantities of premium motor fuel, or premium blending stocks for such motor fuels, can be produced from natural gas, or other mixtures of low molecular weight hydrocarbons consisting essentially of paraffin hydrocarbons of at least four carbon atoms per molecule, comprising predominantly normal paraffins, especially normal butane, normal pentane, and the like. In one modification of my process I subject such a mixture to a fractional distillation, or a series of fractional distillations, and separate from said mixture a fraction comprising essentially a low boiling isoparaffin and another fraction comprising essentially the corresponding normal paraffin. A portion of this second fraction is then subjected to dehydrogenation to form low boiling olefins, which are then reacted either with the isoparaffin or with olefins produced from at least a portion of the isoparaffins by dehydrogenation. A further portion of the normal paraffin fraction is subjected to an isomerization treatment to convert at least a part thereof into the corresponding isoparaffin, and a hydrocarbon material containing isoparaffins so formed is passed along with fresh hydrocarbons, to the aforesaid fractional distillation. The reaction of olefins produced directly from a portion of the normal paraffins with the isoparaffins may be effected either directly with isoparaffins, with or without the presence of catalysts, or may be effected with iso-olefins resulting from dehydrogenation of the isoparaffin. While all the conversion steps may be carried out in the absence of catalytic materials, it is preferable to employ appropriate catalysts throughout for the dehydrogenations, isomerization, alkylation or reaction of olefins and isoparaffins directly, and/or polymerization or reaction of normal olefins and iso-olefins. The invention is particularly applicable to butane or pentane fractions from natural gas or other natural accumulations of hydrocarbons, since these fractions in nearly all cases contain considerably more normal paraffins than the corresponding isoparaffins. By a practice of the invention it is possible to produce highly branched liquid hydrocarbons in amounts considerably greater than twice the weight of the isoparaffins in the original charge stock.

It is an object of my invention to produce a premium motor fuel in high yields from low molecular weight paraffin hydrocarbons.

It is a further object of this invention to produce large quantities of highly branched aliphatic hydrocarbons in the motor fuel range from low boiling paraffin hydrocarbons predominating in normal paraffins.

Another object of my invention is to produce motor fuel stocks of high antidetonating qualities and low vapor pressures.

A further object of this invention is to produce a paraffinic motor fuel of premium quality from a hydrocarbon material comprising predominantly or consisting essentially of normal butane.

A further object of this invention is to produce a paraffinic motor fuel of premium quality from a hydrocarbon material comprising predominantly or consisting essentially of normal pentane.

Further objects and advantages of my invention will become apparent from the accompanying disclosure and discussion.

A particular modification of the present invention will now be described in connection with

the accompanying drawing which forms a part of this specification, and which shows diagrammatically an arrangement of apparatus for practicing my invention. This description will also serve as an illustrative example of my invention.

Referring now to the drawing, a butane fraction comprising predominantly normal butane, such as a butane fraction from a natural gas containing 20 to 25 per cent isobutane and 80 to 75 per cent normal butane, is introduced to the process through pipe 10 and valve 11 to fractional distillation means illustrated by fractional distillation column 12. Such a fractionating column is of the usual bubble tray type, with liquid reflux, suitable heating means for the bottom illustrated by coil 13, and suitable cooling and reflux means for the top, illustrated by coil 14. In this distillation means the hydrocarbon material is separated into an isobutane fraction and a normal butane fraction, each in a substantially pure state and preferably consisting of 95 per cent or more of the respective hydrocarbon. Any undesirable lower boiling material is removed from the system through pipe 15 and valve 16, 20 and any undesirable higher boiling material is removed through pipe 17 and valve 18. If substantially only butanes are charged to the fractional distillation, a single distillation column may be used, operating with about 60 bubble plates 25 under a pressure of about 85 pounds per square inch gauge with a bottom temperature of about 150° F., a top temperature of about 115° F., and a reflux ratio of about 30:1.

The normal butane fraction is passed from a 30 low point of the fractionating column through pipe 20, and a portion is passed through valve 21 to dehydrogenator 22. If desired a normal butane fraction from an outside source may be passed to the system through pipe 33 and valve 40 34 to pipe 20, if such is available. In some instances such a normal butane fraction may constitute the entire charge to the process, with no material being added directly through pipe 10. The dehydrogenation carried out in dehydrogenator 22 is preferably carried out in the presence of a suitable catalyst such as unglowed chromium oxide, bauxite, mixtures of chromium oxide and other oxides, and the like, under low pressures and dehydrogenating temperature 45 about 900 to 1200° F. to form essentially butenes and free hydrogen. The effluent of the dehydrogenation is passed through pipe 23 to separating means 24, with suitable intermediate cooling and compression by means not shown. The temperature and pressure of the material entering the separator means 24 is such that substantially all the C₄ and any C₃, and higher boiling hydrocarbons are in a liquid state. Gases containing free 50 hydrogen and any low boiling hydrocarbons such as methane are removed through pipe 25 and valve 26. Liquefied hydrocarbons comprising essentially normal butane and butenes, pass from separator 24 through pipe 27. If desired, a portion of this material may be returned to the dehydrogenation step by being passed from pipe 27 through pipe 28 and valve 29 to pipe 20, as shown. In this manner the olefin content of the hydrocarbon stream discharged from separator 24 for subsequent treatment, to be described, will 55 be increased beyond that which would be possible from a simple single-pass operation after the system has attained a steady state of operation.

A further portion of the normal butane fraction passing through pipe 20 is removed therefrom through pipe 30 and valve 31 and passed to

an isomerizer 32. In isomerizer 32 the normal butane fraction is contacted with a suitable isomerization catalyst, such as aluminum chloride or bromide, alone or on a suitable support, and at a temperature preferably between about 100 and 400° F. The isomerization reaction is preferably carried out in the presence of a small amount of a hydrogen halide, such as hydrogen fluoride, chloride, or bromide. Such a material may be added, as desired or necessary, through pipe 35 and valve 36 to pipe 30. When a fluid isomerization catalyst is used, it may also be added through pipe 35, but in most cases a solid catalyst will be used, as will be hereinafter discussed in more detail. Under essentially equilibrium conditions the maximum amount of isobutane in the butane fraction of the hydrocarbon effluent from such an isomerization is generally of the order of 65 to 85 per cent. However, in connection with the present invention it is generally desirable not to obtain the maximum amount of isomerization possible at the isomerization conditions, and for most commercial operations I prefer to limit the reaction conditions so that only between about 30 and 60 per cent of the butanes in the effluent consists of isobutane. A similar limitation is preferably used in connection with the extent of isomerization of normal pentane and the like. Such a limitation is quite favorable to the life of the isomerization catalyst and at the same time the amount of products produced by undesirable side reactions is restricted. Since my process includes a co-operative combination of fractionation, isomerization, and conversion such a limitation is not unduly restrictive from the point of view of net yield, and is one of the advantages of the present invention.

The effluent of the isomerizer 32 is passed through pipe 37 and valve 38 to separating means 40. Separating means 40 will consist of various filters, washers, fractionators and the like suitable for the particular modification of operation used. Thus, when a solid isomerization catalyst such as aluminum chloride supported on pumice, silica gel, or charcoal is used, with a small amount of added hydrochloric acid, the effluent may be treated by fractional distillation to remove the hydrogen chloride, or by an alkali wash or the like. Low boiling undesired material may be removed through pipe 41 and valve 42, and high boiling material such as high boiling hydrocarbons, tar, or spent isomerization catalyst may be removed, as through pipe 43 and valve 44. A butane fraction comprising both isobutane and normal butane is passed from separating means 40 through pipe 45 and valve 46 and may be introduced to the fractional distillation means 12 through valve 47.

An isobutane fraction is passed from a high point of the fractionating means 12 through pipe 50. When the polymerization step, to be described, is a part of the process, at least a portion of the isobutane fraction is passed through valve 51 to dehydrogenator 52 for conversion by dehydrogenation to low boiling olefins. As will be more fully discussed hereinafter, a portion or all of the isobutane fraction may be passed from pipe 50 through pipe 53 and valve 54 to the alkylation step in alkylation unit 90. The dehydrogenation effected in dehydrogenator 52 is preferably also carried out in the presence of a dehydrogenation catalyst such as unglowed chromium oxide, bauxite, or the like, at temperature of about 900 to 1200° F. and low pressures to form

mainly free hydrogen and isobutene. The effluent of the dehydrogenation is passed through pipe 55 to separating means 56, with suitable intermediate cooling and compression by means not shown.

5 The temperature and pressure of the material entering the separating means 56 is such that substantially all C₄, and any C₃, and higher boiling hydrocarbons are in a liquid state. Gases 10 containing free hydrogen and any low boiling hydrocarbons such as methane are removed through pipe 57 and valve 58. Liquefied hydrocarbons, consisting essentially of isobutane and isobutene, and at times along with some propene if the dehydrogenation operation in unit 52 is carried out 15 with a large extent of conversion or carried out at least in part in the absence of a catalyst, are passed from separating means 56 through pipe 60. If desired a portion of the material may be returned to the dehydrogenation step by being 20 passed from pipe 60 through pipe 62 and valve 63 to pipe 50 at the inlet of dehydrogenator 52, as shown.

The polymerization of isobutene is preferably conducted in the presence of a catalyst and in 25 the presence of normal butenes produced in dehydrogenator 22, previously discussed. In this manner high yields of highly branched iso-octenes and/or isododecenes are produced. The hydrocarbon stream containing normal butane and normal butenes is passed from separating means 30 24 through pipe 27 and valve 66 to the polymerization unit 67. Polymerization unit 67 will comprise suitable pumps, heating and cooling units, polymerization catalyst chambers, and the like, 35 known to the art. All or a part of the stream containing isobutane and isobutene is passed to the polymerization unit 67 from separating means 56 through pipe 60 and valve 61 to pipe 27. The polymerization conditions in the unit 67 40 are preferably such that normal butenes and isobutene undergo a union with each other, or copolymerization. This is preferably best accomplished by maintaining a polymerization temperature such that normal butenes polymerize with 45 themselves only slowly while in contact with the catalyst used and by maintaining a relatively low concentration of isobutene. This may be accomplished by adding isobutene through a number of pipes, represented by pipe 64 and valve 50 65 55 leading from pipe 60 to an intermediate point of polymerization unit 67, as described in more detail in the copending application of Frederick E. Frey, Serial No. 294,377, filed September 11, 1939. The olefin concentration of the streams passing through pipe 27 and/or pipe 60 may be increased if desired by suitable separation of paraffins and olefins in apparatus not shown, but the increased operating expense is not warranted in most operations.

60 The polymerization effluent, containing olefin polymers along with unreacted hydrocarbons which will be predominantly butanes, is passed through pipe 70 and valve 71 to suitable separating means represented by fractionator 72, with a heating means 73 for the kettle and a cooling and condensing means 74 for the top, and which in actual practice will generally comprise at least two conventional distillation columns, with their regular equipment. A polymer fraction in the motor fuel boiling range is removed 65 through pipe 75 and valve 76. This fraction may be subjected to further fractionation, as may be desired, and also be treated chemically, as by nondestructive hydrogenation using hydrogen produced in the process and discharged through 70 75

pipe 25 and/or pipe 57. A butane fraction, comprising both normal butane and isobutane, is removed through pipe 71, and may be passed through valve 78 to the fractional distillation means 12. In some instances, however, it is preferable not to mix this butane fraction with a butane fraction charged to the system. The isomerization catalysts used in isomerizer 32 generally react quite readily with unsaturated hydrocarbons, and these latter tend to act as undesirable contaminants in the charge to the isomerization step. Since the unreacted butane fraction from the polymerization step generally contains a small amount of butenes, it is better that these butenes do not find their way to the isomerizer 32. I prefer to pass the butane fraction from separating means 72 through pipe 71 and through pipe 100 and valve 101 to a separating means represented by fractional distillation column 102, provided with suitable heating means 103 for the bottom and suitable cooling and condensing means 104 for the top. A normal butane fraction, containing a small amount of unreacted butenes, is then passed from a low point of the distillation column 102 through pipe 105 and valve 106 to the butane stream entering the dehydrogenator 22 through the latter part of pipe 20. An isobutane fraction, which will also contain a small amount of olefins, is passed from the top of the column 102 through pipe 107 and valve 108 to be mixed with the isobutane fraction passing from separating means 12 through pipe 50. That portion of the normal butane fraction passed to isomerizer 32 is thereby not contaminated by unreacted olefins produced in the process, and at the same time efficient separation and recycling of specific hydrocarbon fractions is realized.

Lower boiling hydrocarbons, or any undesired low boiling material, may be discharged from the separating means 72 and from the process through pipe 80 and valve 81, and if desired a part or all of the butane and lighter fraction may be so discharged. If this latter procedure is followed, the butane fraction may be subjected to any desirable further treatment, and returned to the process through pipe 10. Olefin polymers boiling above the range of the material discharged through pipe 75 may be separated from higher boiling material and passed through pipe 83 and valve 84 to pipe 91 and the alkylation step, to be described. Higher boiling material, which may on occasion include a substantial part or all of any material higher boiling than the motor fuel fraction removed through pipe 75, is discharged from the system through pipe 85 and valve 86. It is, of course, understood that the characteristics of various particular products removed will be dependent on the desired characteristics of the motor fuel stock being produced and on the material charged, and the fractionating equipment used and its conditions of operation will be such as best adapted to the particular needs of the specific requirements at hand, as may be readily determined by one skilled in the art.

The charge to the alkylation step will consist of isobutane along with olefins produced from the normal butane fraction, either directly by simple dehydrogenation or somewhat indirectly by the use of heavier olefin polymers which are passed through pipe 83 as just discussed. A portion or all of the isobutane fraction passing from fractionating means 12 through pipe 50, along with that passed through pipe 107 from fractionator 102, is passed through pipe 53 and valve 54 to the

alkylation unit 90. A portion or all of the normal butenes produced in dehydrogenator 22 may be passed directly from separating means 24 through pipe 27 and through pipe 91, and valves 92 and 93 to be mixed with the isobutane fraction entering the alkylation unit 90. Alternatively, or concomitantly, the aforementioned heavier olefin polymers may be introduced through pipe 83 to pipe 91 and passed to the alkylation step.

As will be discussed more fully hereinafter, either a solid stationary alkylation catalyst or a fluid alkylation catalyst such as concentrated sulfuric acid, or the like, or concentrated hydrofluoric acid, may be used. Fresh portions of such a fluid alkylation catalyst are introduced through pipe 96 and valve 97 to the alkylation unit 90. While it may be passed more directly to the alkylation step, it is more preferably mixed with the hydrocarbon material passing through pipe 53. In general it is desirable to keep the olefin concentration low during the alkylation process, as disclosed in Frey's Patent 2,002,394, and the olefin-containing stream may be added at a number of points along a reaction zone through a number of pipes, represented by pipe 94 and valve 95, through which is passed a portion of the olefin-containing stream from pipe 91 to an intermediate point of alkylation unit 90. The effluent of the alkylation is passed through pipe 98 to a catalyst separator 110. When a liquid catalyst such as concentrated sulfuric acid or concentrated hydrofluoric acid is used, the catalyst separator will generally include a settling and separating tank, or the like, for the separation of the main part of the catalyst from the hydrocarbon part of the effluent. The catalyst is then withdrawn through pipe 111 and valve 112 for further concentration, purification and other treatment, and if desired a part or portion of it may be recycled directly to the alkylation step through pipe 113 and valve 114 to pipe 96. In such a case the catalyst separator will also generally include some means for removing traces of acidic material from the hydrocarbon material, such as an alkali wash, or the like. The hydrocarbon material is then passed through pipe 115 and valve 116 to fractionating means represented by the distillation column 120, provided with suitable heating means 121 and cooling and condensing means 122.

An alkylate fraction, containing normally liquid hydrocarbons produced in the alkylation step, is removed through pipe 123 and valve 124. This fraction may contain some definite controlled amount of normal butane, to furnish a desired volatility and vapor pressure, and this alkylate fraction may serve directly as a motor fuel, or as a motor fuel blending stock, and may be further treated and fractionated as desired. Any undesirable low boiling products may be separated from the fractionating means 120 and from the process through pipe 125 and valve 126. A butane fraction is removed through pipe 130 and may be returned in part to the alkylation step through valve 131 to pipe 53. At least a part of this butane fraction will generally be subjected to fractionation to separate isobutane and normal butane. In many instances this is preferably done by passing the fraction to fractionating means 102 from pipe 130 through pipe 132 and valve 133 to pipe 100. Any portion of this butane fraction, if desired, may be fractionated in fractionating means 12 by being passed from pipe 132 through pipe 134 and valve 135 to pipe 71, especially when this stream is substantially olefin-

free, as is often true for this part of the effluent of a catalytic alkylation step.

The introduction of the hydrocarbon streams passing through pipes 10, 45, and 77 has been described as being made at different points to fractionating column 12. This is especially to be preferred when the charge stock to the process contains only a small amount of isoparaffins and the isomerization is conducted to produce isoparaffins in the higher part of the range discussed. However, in many cases it will be satisfactory to introduce any two or all three of the streams at a single point, with suitable control of valves 141 and 142 in pipe 140 and of valve 144 in pipe 143. When both the polymerization and the alkylation steps are used, a portion or all of the unreacted butane effluent from the polymerization may be passed from pipe 77 through pipe 145 and valve 146 to pipe 53 and the alkylation step, with suitable control of valves 101 and 79.

I also contemplate as a part of my invention, the treatment of a mixture of pentanes in substantially the same manner as has just been described for a mixture of butanes. When treating a mixture of pentanes, the isopentane will pass overhead from the fractionating column 12 as did the isobutane as described. Likewise normal pentane will pass from the bottom of the column and may be treated in accordance with the treatment of normal butane described. Although a third pentane, neopentane or tetramethyl methane is known, its presence in naturally-occurring hydrocarbon materials has not been observed in any great amount. If such neopentane should be present, it can readily be separated from the isopentane-normal pentane mixture before this mixture is introduced to my process, or may be removed through pipe 15 and valve 16. Somewhat different temperatures of dehydrogenation, isomerization, polymerization, and/or alkylation may need to be used when using isopentane instead of isobutane and when using normal pentane instead of normal butane, but these conditions will not be widely different from corresponding conditions for the butanes and may be readily ascertained by one skilled in the art, for any particular case. The isopentenes produced by the dehydrogenation of isopentane will be predominantly tertiary-base olefins and will react with normal pentenes produced from normal pentane in a manner analogous to that herein described for the copolymerization of isobutene with normal butenes. Normal pentenes will react with isopentane in the alkylation step under only slightly more drastic conditions than those used when a butane is being treated by the invention. Under some conditions of isomerization of normal pentane, especially with an extended conversion of normal pentane, appreciable amounts of isobutane are produced as well as isopentane. This isobutane may be retained in the isopentane fraction passed through pipe 50 and will undergo concomitant conversion into motor fuel in a subsequent step.

It is a feature of my invention that the process is quite flexible, and readily adapted to handle charge stocks of various proportions of normal and isoparaffins, and to produce large quantities of either paraffinic or olefinic, highly branched liquid hydrocarbons. If desired, either the polymerization or the alkylation steps may be practiced alone to the exclusion of the other. In one case an olefin produced from normal butane is reacted with an olefin produced from isobutane and in the other case an olefin produced from

normal butane reacts directly with isobutane. In both cases, all the normal butane charged to the process eventually appears in the highly branched liquid hydrocarbon product, either directly through a normal olefin reaction step or indirectly through isomerization to isobutane, except of course for the material lost through unavoidable side reactions. In many instances a completely paraffinic product is desired, and in such a case the alkylation step produces this product directly while similar paraffin hydrocarbons may be produced in the process through polymerization and subsequent saturation of the polymers with hydrogen previously produced within the process by dehydrogenation. When an olefin-containing motor fuel stock can be used, a product with a high unleaded octane number (that is, before the addition of an antidetonating agent such as tetraethyl lead) can be produced by blending the olefin polymers produced in the polymerization step with the paraffinic product produced by the alkylation step. The product from the polymerization step has an octane number of about 82 and from the alkylation step of about 90 to 96. While the polymer product, when saturated with hydrogen, also has an octane number within the range of 90 to 96, without such saturation it has a blending octane number of about 130 when blended directly with a paraffinic fuel and in amounts not greater than about 30 per cent by volume. I therefore prefer to operate my process to produce a single product with both the polymerization and alkylation steps, the product containing about 5 to 30 per cent, preferably 15 to 25 per cent, of olefin polymers and the remainder paraffinic material comprising paraffins produced by the alkylation step. The two steps can be made to cooperate further by passing any polymers too heavy for the desired motor fuel stock to the alkylation step under conditions adapted to react isobutane, or isopentane, with these heavy polymers to produce liquid paraffins in the desired motor fuel range.

In most cases any known isomerization process may be used in connection with isomerizer 32, although of course such processes are not to be considered complete equivalents of each other either as to operating conditions or yields. However, any such process can be operated by one skilled in the art to produce an effluent, the predominant part of which is a hydrocarbon fraction of the same number of carbon atoms as the normal paraffin charged and containing appreciable quantities of the desired isoparaffin; and an advantage of the invention is that the process disclosed herein will adequately handle any such product. A highly desirable operation can be secured by using aluminum chloride or aluminum bromide, preferably deposited on a highly porous support such as activated charcoal or dried silica gel, or the like. The temperature is preferably in the lower part of the range of 160 to 400° F., and while the process may be operated with the reactants substantially in the gaseous phase, I prefer to operate with sufficient pressure to maintain the reactants in liquid phase and with the time of reaction so limited that the amount of isoparaffin in the effluent is not greater than about 80 per cent of what it would become if the time were sufficient for an equilibrium between the normal paraffin and the isoparaffin. As previously indicated, the fraction of the product corresponding to the normal paraffin charged will preferably contain 30 to 60 per cent of isoparaffin. As mentioned, it is desirable that the charge to

the isomerizer should be substantially free of unsaturated hydrocarbons, and a second butane, or pentane, fractionation means 102 has been described to accomplish this result. In some instances it may be desirable to submit the material passing through pipe 30 to isomerizer 32 to further treatment, as with concentrated sulfuric acid in means not shown, to remove small amounts of unsaturated material, or other contaminants, which may be present.

While any of a number of dehydrogenation catalysts may be employed in the dehydrogenation chamber 22 and in dehydrogenation chamber 52, I prefer to use a chromium oxide-containing catalyst such as described by Huppke and Frey in U. S. Patent 1,905,383, or in U. S. Patent 2,098,959, bauxite with deposited chromium oxide, certain hard bauxites alone, or the like. When dehydrogenating isobutane, I prefer to operate at a temperature within the range of 750 to 1150° F. and when dehydrogenating normal butane, I prefer to operate at a slightly higher temperature such as one within the range 800 to 1250° F. If my process is used to treat a mixture of isopentane and normal pentane I prefer to dehydrogenate isopentane, using such a catalyst, at a temperature between 700 and 1100° F. The normal pentane should be dehydrogenated at a temperature between about 725 and 1150° F. In all such dehydrogenation operations I prefer to operate at a pressure at or near atmospheric. If the pressure is above atmospheric, it should not be more than 50 or 100 pounds per square inch pressure above atmospheric.

I prefer to use a solid polymerization catalyst in polymerizer 67 for the polymerization of the olefins although this is not always necessary. Such a solid catalyst may be one prepared from hydrous silica intimately associated with hydrous alumina such as the silica-alumina catalysts described by McKinney in Patent 2,142,324 or 2,147,985, and in the copending application of Frey, Serial Number 329,195, filed April 11, 1940 or one of the well known solid phosphoric acid catalysts, or may be zinc halide or similar halide deposited upon an inert support such as silica, pumice stone and the like.

While I prefer an operation in connection with a solid catalyst, nevertheless I do not desire necessarily to be restricted to the use of a solid catalyst. Operations are known in which liquid catalysts are quite suitable for the polymerization of olefins, such as sulfuric acid of about 75 per cent concentration in aqueous solution, strong phosphoric acid, various sulphonic acids and the like. While I may use any such catalyst in my process, I do not consider that one catalyst is the equivalent of another catalyst either as to preferable operating conditions or as to the products produced, but there will be minor variations between each catalyst when at their optimum operating conditions.

The polymers produced when using pentanes as a charge stock to my process will consist principally of decenes which will be highly branched and which, upon hydrogenation, will have high octane numbers and will be quite suitable for use in relatively nonvolatile aviation fuels and the like. With the exception of slight obvious changes in operating conditions to compensate for the difference in reactivities of pentanes and the corresponding butanes and pentenes and the corresponding butenes, such a process to which is charged a mixture of isopentane and normal pentane can be operated in substantially the man-

ner I have described for operating with a mixture of isobutane and normal butane.

The alkylation step is preferably conducted in the presence of an alkylation catalyst. Any one of a number of known alkylation catalysts may be used, although not under completely equivalent conditions nor with completely equivalent results. Catalysts which may be used in my alkylation step include aluminum chloride and bromide, concentrated sulfuric and sulphonic acids, concentrated hydrofluoric acid, sodium chloroaluminate, and other known mixtures of aluminum chloride or bromide with metal halides, especially halides of the alkali metals. I prefer to use concentrated sulfuric acid or concentrated hydrofluoric acid, with the acid and reactants in liquid phase and with the reaction conducted at a temperature between about 0 and 100° F. The ratio of liquid acid to liquid hydrocarbon material should be between about 1:10 and 1:1, with intimate mixing and emulsification of the acid and reactants and with suitable means for removal of heat of reaction. As one means of accomplishing this, the reaction mixture may be rapidly passed through a tube coil of restricted cross sectional area immersed in a cooling bath. The olefin concentration in the reacting mixture in any case is preferably kept at a low value, and rather than initially mixing a large portion of olefins and isoparaffins and passing the resultant mixture through the alkylation zone I prefer to add olefin during a reaction period of about 15 minutes to 2 hours. The rate of addition will be somewhat dependent on other operating conditions, and can be readily determined by trial for any particular case. Preferably the olefin containing material is added to the paraffinic stream in contact with the catalyst at a plurality of intermediate points, as discussed.

40 Numerous adaptations and variations of this invention may obviously be used and applied by one skilled in the art without departing from the spirit of the disclosure. It will be understood that the flow diagram is illustrative and that many 45 additional conventional pieces of equipment, such as pumps, heat exchangers, heaters, coolers, reflux lines and accumulators, gauges and valves, and the like will be necessary for any particular installation and can be supplied by one skilled in the art for any particular installation. No pumps 50 have been shown, but the operating conditions for each step are discussed or well known, and with the material flows shown specific pumps for specific arrangements become obvious.

55 I claim:

1. An improved process for converting butanes to an aliphatic motor fuel stock, which comprises separating from a first butane fractionating means an isobutane fraction and a normal butane 60 fraction, subjecting a first portion of said normal butane fraction to isomerization to form a butane mixture and passing same to said first butane fractionating means, dehydrogenating a second portion of said normal butane fraction to form a normal butenes fraction, dehydrogenating at least a portion of said isobutane fraction to form an isobutene fraction, copolymerizing olefins in a first portion of said normal butenes fraction and in said isobutene fraction to form copolymers boiling in the motor fuel range, separating from effluents of said copolymerization a copolymer fraction so produced and a C₄ fraction containing unreacted butenes, passing at least a portion of said C₄ fraction to a second butane 70 fractionating means, removing from said second 75 fractionating means, removing from said second

2,389,984

means an iso C₄ fraction and a normal C₄ fraction, admixing said normal C₄ fraction with said second portion of said normal butane fraction, passing said iso C₄ fraction to alkylating means, passing also to said alkylating means a second portion of the aforesaid normal butenes fraction and reacting normal butenes contained therein with isobutane in said iso C₄ fraction to form isoparaffins boiling in the motor fuel range, separating from effluents of said alkylation a C₄ fraction and passing same to the aforesaid second fractionating means, separating also from said alkylation effluents an isoparaffinic fraction so produced, and blending said copolymer fraction and said isoparaffinic fraction to form an aliphatic motor fuel stock containing between 5 and 30 per cent of olefins.

2. An improved process for converting isoparaffins and normal paraffins of the class consisting of butanes and pentanes to an aliphatic motor fuel stock, which comprises separating from a first hydrocarbon fractionating means an isoparaffin fraction of said class and a normal paraffin fraction of said class, subjecting a first portion of said normal paraffin fraction to isomerization to form a paraffin mixture containing isoparaffins and passing same to said first hydrocarbon fractionating means, dehydrogenating a second portion of said normal paraffin fraction to form a normal olefin fraction, dehydrogenating at least a portion of said isoparaffin fraction to

form an iso-olefin fraction, copolymerizing olefins in a first portion of said normal olefin fraction and in said iso-olefin fraction to form copolymers boiling in the motor fuel range, separating from effluents of said copolymerization a copolymer fraction so produced and a hydrocarbon fraction containing unreacted paraffins and olefins, passing at least a portion of said unreacted hydrocarbon fraction to a second hydrocarbon fractionating means, removing from said second means an isoparaffin fraction and a normal paraffin fraction each containing a small amount of olefins, admixing said normal paraffin fraction with said second portion of the first said 10 normal paraffin fraction, passing the last said isoparaffin fraction to alkylating means, passing also to said alkylating means a second portion of the aforesaid normal olefin fraction and reacting normal olefins contained therein with isoparaffins 20 in said isoparaffin fraction to form isoparaffins boiling in the motor fuel range, separating from effluents of said alkylation a low-boiling paraffin fraction and passing same to the aforesaid second hydrocarbon fractionating means, separating 25 also from said alkylation effluents a motor fuel range isoparaffinic fraction so produced, and blending said copolymer fraction and the last said isoparaffinic fraction to form an aliphatic motor fuel stock containing between 5 and 30 per cent of olefins.

JEAN P. JONES.
